STOVE.

No. 16,196.

Patented Aug. 11, 1885.

UNITED STATES PATENT OFFICE

JAMES DWYER AND JOHN W. HERRICK, OF DETROIT, MICHIGAN.

DESIGN FOR A STOVE.

SPECIFICATION forming part of Design No. 16,196, dated August 11, 1885.

Application filed June 15, 1885. Term of patent 7 years.

To all whom it may concern:

Be it known that we, JAMES DWYER and JOHN W. HERRICK, of Detroit, in the county of Wayne and State of Michigan, have invented 5 a new and useful Design for Stoves, of which the following is a specification.

The photograph shows the stove in perspective.

The stove is a magazine-stove, and in general shape is rectangular, with a swell front terminating in a receding arch just below the upper molding or cornice.

Beginning with the lower section or base, the shape and configuration of the stove are as follows: The base curves from its upper surface downward, and rests upon a skirt, which between the legs is beveled upward from each side toward the center and ornamented with scroll-work and rosettes. The section above 15 the base, forming the ash-pan chamber, is ornamented with rustic work on the ash-door around the damper-openings, and with scroll-work on the sides. The next section, which surrounds the lower portion of the fire-pot, 20 consists on the sides and front of open-work doors to be filled in with mica, having a frame, a center rib, and rosettes connecting the frame and rib. The next section, surrounding the fire-chamber and the lower end of the magazine, is made up of open-work doors similar 25 to those below, but with two ribs instead of one, and double rosettes connecting the ribs. The next section above has its sides paneled 30 in arches, with raised ornamentation and an arched front, in which is a curved piece with 35 raised ornamentation curving outward and

downward to meet the swell front. On each corner of this section is a lion's head set in a conventional figure. The top section of the stove curves on all sides outward and downward from the center portion which supports the magazine-cover, and is divided into panels bearing raised ornamentation by plain bands. 4c

The magazine-cover is rectangular in form at its base, and its top is arched, the top and 45 each side forming a panel, on which is raised ornamentation.

The foot-rails are carried on the sides of the stove by griffins.

We claim—

The herein-described design for a stove, consisting of a rounded ornamented base having legs and a skirting with rosette ornamentation, a rustic-work section surrounding the ash-pan chamber, open-work doors with rosette in the section surrounding the fire-pot, similar doors but of greater height in the section around the fire-chamber and the lower end of the magazine, an ornamental arched section above the latter, in which is a curved 50 piece having a raised ornamentation bearing the representation of the head of a person, a top divided into panels carrying raised ornamentation by plain bands, and an arched magazine-cover having paneled front and 55 sides, the whole forming a rectangular magazine-stove with swell front.

JAMES DWYER.
JOHN W. HERRICK.
